UNITED STATES PATENT OFFICE.

HENRY A. JOHNSON, OF CHICAGO, ILLINOIS.

CARBURETER.

1,069,335.

Specification of Letters Patent.

Patented Aug. 5, 1913.

Application filed September 23, 1910. Serial No. 583,440.

To all whom it may concern:

Be it known that I, HENRY A. JOHNSON, a citizen of the United States of America, and a resident of Chicago, county of Cook, 5 State of Illinois, have invented certain new and useful Improvements in Carbureters, of which the following is a specification.

The main objects of this invention are to provide an improved carbureter for internal 10 combustion engines of the class where a part of the air supply is drawn through the liquid fuel instead of spraying the liquid into the moving air; to provide a construction in which a relatively coarse adjustment 15 of the level of the fuel in the carbureter will secure complete saturation; to provide means for removing an excess of liquid in the vapor; and to provide improved means which will prevent loss of fuel due to over- 20 flow.

A specific construction embodying this invention is illustrated in the accompanying drawings, in which

Figure 1 is a vertical sectional view of the 25 complete carbureter, the tank being shown diagrammatically. Fig. 2 is a horizontal sectional view of the hood covering the air inlet. Fig. 3 is a detail view of the fuel inlet valve.

In the construction shown, the main air supply is provided for by an air inlet pipe 1 which projects upwardly through the bottom of the casing 2 to a position above the normal liquid fuel level 3. Covering the 30 air inlet pipe 1 is a flat top and flute-sided hood 4 having an integral flared fluted skirt 5. The side fluting makes a sliding fit with the outer side of the air inlet pipe 1. To the under side of the top of the hood is 35 fastened a rod 6, to which is secured a spring 7 normally holding the hood 4 in liquid tight contact with the top of the inlet pipe 1. The fuel supply is delivered through a pipe 8, which passes through one of the vertical walls of the casing 2. The inner end 40 of the pipe 8 is provided with an outlet 9, which is at the normal fuel level 3. A special pipe 10 extends from the top of the supply tank 11 to liquid fuel level 3. The fuel 45 inlet pipe 8 is also provided with a needle valve 12 which slides through a guide box 13, and is pivoted to the lever arm 14. The short end of the lever arm 14 is pivoted to the inner wall of the casing at 15. The long 50 end of the lever arm is pivoted to the center of a float 16.

Excess liquid is removed from the vapor by a series of gravity draining baffle plates 17, 18, 19, and 20, said baffle plates being so placed as to form a tortuous passage for 60 the vapor from the level of the fuel to the main outlet 21. The main vapor outlet 21 is provided with an outlet pipe 22 secured to the casing by screws 23, 23, and to the top of this outlet pipe is secured a T-fitting 24, 65 one end of which is provided with an auxiliary air valve 25, said air valve being normally held on its seat 26 by a spring 27 secured to an adjusting screw 28. The end of the pipe 24 opposite the auxiliary air 70 valve 25 is connected to the engine.

In operation, the maintenance of the level of the fuel supply is provided by placing the outlet 9 of the fuel inlet pipe 8 and the inlet of the special air pipe 10 at the normal 75 level of the liquid fuel 3. The carbureter, when operated with a closed supply tank, will maintain the fuel level automatically at the position of the outlet 9, due to the pneumatic action of the supply tank. In 80 case the supply tank is not hermetically closed, reliance is placed upon the action of the float 16. The float 16 is raised by the rise in the level of the fuel, and the fuel inlet pipe 8 is closed by the movement of the 85 needle valve 12, which is controlled by the float. In this carbureter, the float 16 is in action only when the pneumatic control fails, and the level of the liquid rises above the normal working level 3. Closure of the 90 fuel inlet pipe by the action of the needle valve 12 will take place before the level of the liquid fuel rises above the top of the air inlet pipe 1. If for any reason it is found necessary to depend on the needle 95 valve to maintain the fuel level, then spilling of the fuel through the air inlet pipe will be prevented by the seating of the flat top of the hood on the upper end of the air inlet pipe.

The mixture of the air with the liquid fuel is accomplished through the suction stroke of the engine to which the carbureter is connected; and air pressure lifts the hood 4, allowing air to enter the casing by passing 105 under the hood. The fluting on the sides of the hood 4 acts as a guide to the movement of the hood, and at the same time forms separate passages which subdivide the charge of air taken by the carbureter. All 110 the air entering the carbureter must pass through the liquid fuel from the lower edge

of the flared skirt 5 of the hood 4. The flared and fluted skirt 5 of the hood 4 produces a uniform distribution of the air through the mass of the liquid fuel. As the air leaves the fuel, it carries along with it a small quantity of the liquid in suspension, which is not vaporized, and the excess of liquid in the vapor is removed by coming in contact with both the lower and upper surfaces of the baffle plates 17, 18, 19, and 20, which are disposed between the fuel level 3 and the outlet 21, so that the vapor strikes first the baffle plate 17 where it is drawn toward the center of the carbureter, next against the under side of the baffle plate 18, where the vapor must pass between the periphery of the baffle plate 18 and the casing 2, and in a similar manner to the center of the baffle plate 19, thence around the periphery of the baffle plate 20 to the outlet. When the vapor reaches the outlet 21 it is fully saturated. The thinning of the mixture so as to produce a rapid firing mixture is accomplished by admitting air to the mixture through the auxiliary air valve 25. The adjustment of the amount of air taken through the auxiliary air valve and its relation to the suction of the engine is controlled by adjustment of the tension of the spring 27 through the holding screw 28, which is provided with a threaded surface.

Although but one specific embodiment of this invention is herein shown and described, it will be understood that numerous details of the construction shown may be altered

or omitted without departing from the spirit of this invention, as defined by the following claims.

I claim:

1. A carbureter, comprising a casing adapted to contain a quantity of liquid and having a fuel outlet, an air inlet pipe extending into said casing and terminating above the level of the liquid contained therein, a hood adapted to form a closure for the inner end of said pipe, means yieldingly urging said hood to close said pipe, and a flaring fluted skirt depending from said hood into the liquid for directing the air into the liquid. 50

2. A carbureter, comprising a casing adapted to contain a quantity of liquid, said casing having a fuel outlet and a fuel inlet, means for automatically controlling said fuel inlet to maintain a normal level of the liquid in said casing, an air inlet pipe extending into said casing and terminating above the normal level of the liquid, a hood adapted to serve as a closure for the inner end of said inlet pipe, means yieldingly urging said hood to close said pipe, and an annular flange spaced away from said inlet pipe and depending from said hood into the liquid for directing the air into the liquid. 60

Signed at Chicago this 19th day of September 1910.

HENRY A. JOHNSON.
